HAND-HELD ELECTRIC HAIR DRYER

Martin J. Wolff, West Haven, Conn., and Dov Z. Glucksmann, Brookline, Mass., assignors to Sperry Rand Corporation, Bridgeport, Conn.

Filed June 4, 1975, Ser. No. 583,616

Term of patent 14 years

Int. Cl. D28—03

U.S. Cl. D86—10 F

Fig. 1.

Fig. 2.

Fig. 3.

FIG. 1 is a perspective view of the front and right side of a hand-held electric hair dryer showing our new design;

FIG. 2 is an elevational view of the front of the dryer of FIG. 1;

FIG. 3 is an elevational view of the rear of the dryer of FIG. 1;

FIG. 4 is a top plan view of the dryer of FIG. 1;

FIG. 5 is a right side elevational view thereof; and FIG. 6 is a bottom plan view thereof.

The conventional power cord is shown only partially for convenience of illustration.

We claim:

The ornamental design for a hand-held electric hair dryer, substantially as shown and described.
